UNITED STATES PATENT OFFICE.

GEORGE H. GROTH, OF DAYTON, OHIO.

FLUID-PRESSURE MOTOR.

1,355,962.

Specification of Letters Patent.

Patented Oct. 19, 1920.

Application filed July 3, 1916. Serial No. 107,458.

To all whom it may concern:

Be it known that I, GEORGE H. GROTH, citizen of the United States, residing at Dayton, in the county of Montgomery, and 5 State of Ohio, have invented certain new and useful Improvements in Fluid-Pressure Motors, of which the following is a specification.

My invention relates to pneumatics and 10 more particularly to a motive supply system for pneumatic or other fluid pressure motors.

The object of the invention is to simplify the construction as well as the means and mode of operation of such systems whereby 15 they will not only be cheapened in construction, but will be more efficient in use, positive and uniform in operation, substantially automatic, and unlikely to get out of repair.

A further object of the invention is to 20 provide an improved method or system of compounding the expansive force or energy of the actuating media whereby a higher degree of efficiency and a greater degree of available energy is afforded.

25 With the above primary and other incidental objects in view, as will more fully appear in the specification, the invention consists of the features of construction, the parts and combinations thereof, and the mode of 30 operation, or their equivalents, as herein-after described and set forth in the claims.

Referring to the drawings, Figure 1 is a 35 diagrammatic view of the assembled apparatus and connections comprising the system forming the subject matter hereof. Figs. 2 to 5, inclusive, are diagrammatic views illustrating successive stages in the cycle of operations. Fig. 6 is a detail view of the valve operating means.

40 Like parts are indicated by similar characters of reference throughout the several views.

It is believed that this invention is based first upon the generally recognized law of physics that any degree of intrinsic or stored energy is capable of reproducing itself or creating a like condition less losses due to friction and leakage; and second: to Mariotte's law, viz., "The temperature remaining 45 the same, the volume of a given quantity of gas varies inversely as the pressure." In other words, the product of pressure and volume is constant.

Under the first mentioned rule, given a 50 container of compressed air or gas having a volume of two cubic feet and a pressure of

eighty pounds per square inch, the intrinsic or stored energy or the capacity for work of such body of compressed air or gas is sufficient to effect the charging of a second container of equal volume to an equal pressure 60 less those losses due to friction and leakage.

Under Mariotte's law before stated, the same container having a volume of two cubic feet of air or gas under pressure of eighty 65 pounds per square inch if permitted to expand without loss into a container having a volume of four cubic feet, the pressure will have been decreased to one half or forty pounds per square inch. Multiplying the 70 volume by the pressure in each instance, viz: $2 \times 80 = 160$ and $4 \times 40 = 160$, it will be found that one body is equal to the other or that the inherent energy or capacity for work is the same in both instances. In applying this 75 principle to the present invention, the applicant in lieu of employing a container of double capacity employs a second container of equal capacity into which the air or gas is allowed to expand from the first container 80 until the pressure in the two containers is equalized, whereby the two containers become the equivalent of a single container of double capacity and the pressure in each container is one half the original pressure 85 when contained in the single container.

As stated in Mariotte's law, this condition is dependent upon the temperature remaining the same. In other words, under isothermal expansion or when the absorption 90 of heat is sufficient to compensate for the fall of temperature due to expansion to maintain the air at even temperature under the variation of pressure.

In the present instance an isothermal condition is effected by jacketing or insulating the containers to retain or prevent the disbursement of the heat resulting from high compression and alternating the high and low pressures in the respective containers 95 with rapidity whereby the air is expanded from higher to lower pressure into a container previously heated by the high pressure charge and the charge at high pressure is received in the container previously cooled 100 by the expansion of the air thereinto at lower pressure, the alternation or reversal occurring with such rapidity as to tend to equalize the temperature and to approach a 105 uniform degree of temperature or isothermal condition.

With the aforementioned basic principles

in mind, it is thought that the following description of the invention forming the subject matter hereof may be readily understood.

- 5 As illustrated in the assembly diagram Fig. 1, the operating parts and connections are divided into two series hereinafter referred to as the high pressure and low pressure sides. These high and low pressure 10 series or sides alternate at each succeeding stage of operation. The low pressure side or series during one stage of operation becomes the high pressure side or series during the next stage of operation and vice 15 versa. Likewise, the variable pressure containers or tanks of each side or series hereinafter referred to alternate between high pressure and low pressure in addition to the alternation of high and low pressure 20 between the respective sides or series.

The volumes or capacities of the several tanks or containers and the pressures herein mentioned have been arbitrarily assumed merely for the purpose of illustration. It 25 will be understood that the invention is not limited to any particular relation of pressures or of capacity herein mentioned but that both the volume and pressure may be varied to meet different conditions of use. 30 The required degree of pressures and the relative proportions of the containers or the volume to meet different conditions may be ascertained by mathematical calculation.

Referring to the drawings, 1 is the main 35 reservoir or supply tank to which air is supplied under pressure by the compressor 2. The compressor may be driven by any suitable or convenient means. The fluid pressure motor to be operated comprises the 40 high pressure cylinder 3 and low pressure cylinders 4-4. The actuating media is supplied to the motor from the main reservoir or supply tank 1 through intermediate auxiliary or variable pressure tanks and valved 45 conduits or connections.

As before mentioned, the auxiliary tanks and connections are divided into high and low pressure sides or series. These high and low pressure sides and series are identified 50 one with the other and a description of one will suffice for both except for such incidental references as may be made in explaining the operation. To aid in identifying corresponding parts of the respective 55 sides or series, the same reference characters will be used. Those pertaining to the low pressure side or series, as shown in Fig. 1, are distinguished from the opposite side by the addition of prime marks.

60 The air under compression is carried from the compressor 2 to the main tank or reservoir 1 through the inlet conduit 5 having therein a check valve 6. The main reservoir or tank 1 is of comparatively large 65 size in proportion to the capacity of the

auxiliary or variable pressure tanks herein-after mentioned. The admission of a charge of air into the initial auxiliary or variable pressure tank from the main supply tank will thus cause but a slight lowering of the 70 pressure in the main tank. In the diagram Fig. 1 the capacity of the main reservoir or tank has been assumed as four hundred cubic feet and its maximum pressure as eighty and four tenths pounds per square 75 inch whereby the initial auxiliary or variable pressure container or tank will be supplied at the assumed working high pressure of eighty pounds per square inch. Eighty pounds per square inch will therefore be the 80 minimum supply tank pressure. After each charge is delivered to the auxiliary tank the compressor restores the main tank pressure from eighty to eighty and four tenths (80.4) pounds pressure.

In order that the compressor 2 may not be compelled to operate idly against an excessive high pressure as would be the case if a safety valve as ordinarily used was applied to the tank, there has been provided a relief conduit 7 leading to a cylinder 8 within which is located a piston 9 operated against the tension of a spring 10 by the pressure within the main tank or reservoir 1. Connected to the piston 9 is 95 a valve 11 adapted upon movement of the piston 9 to open a relief port 12 in the compressor conduit 5. The construction is such that when the tank or reservoir 1 has been restored to its maximum or operating pressure the valve 11 will be operated to open the port 12 thereby permitting the compressor 2 to operate idly.

The high or low pressure sides or series of the apparatus comprise two auxiliary 105 or variable pressure tanks or containers A and B and A' and B', respectively, which containers or tanks are suitably jacketed or insulated to retain and prevent the loss of heat. The auxiliary or variable pressure 110 tanks are connected by sundry conduits hereafter separately referred to with two series of valves a, b, c, d, e, f, g, h, i, and series of valves a, b, c, d, e, f, g, h, i, and These valves are arranged in groups and 115 are operated in proper time and sequence by valve operating mechanism controlled by the motor. In Fig. 6 there has been shown valve operating means comprising a cam drum x having thereon a plurality of cam surfaces y engaging and reciprocating in turn the stems z of the several valves a, b, c, d, &c. The cam surfaces y are so positioned in relation one with the other as to secure the proper timing of the valve. The 120 first group of valves comprising the valves a, b, a' and b' are connected by the conduits 13 and 13' and the common conduit 14 with the main or supply tank 1. The second group of valves c, d, c' and d' are con- 130

nected by the conduits 15 and 15' and the common conduit 16 with the intake port of the high pressure cylinder 3. The third group of valves *e*, *f*, *e'* and *f'* are connected by the conduits 17 and 17' and the common conduit 18 with the exhaust port of the high pressure cylinder 3. The fourth group of valves comprising the valves *g*, *h*, *i*, *j*, *g'*, *h'*, *i'*, and *j'* are connected by the conduits 19 and 19' and the common conduits 20 with the intake ports of the low pressure cylinders 4-4. An exhaust conduit 21 leads from the exhaust ports of the low pressure cylinders 4-4 and discharges 15 to atmosphere.

Located in the auxiliary or variable pressure tanks A and B are piston heads 22 and 23 rigidly connected one with the other by an intermediate piston rod 24. Similar piston heads are mounted in the auxiliary tanks of the opposite series. These piston heads are free to move in unison throughout the length of their respective tanks or containers. Leading to the inner or adjacent 20 ends of the auxiliary tanks A, B, and A' and B' are inlets or breathing tubes 25 and 25', each having therein a check valve 26 and 26' adapted to admit air at atmospheric pressure to the tank but preventing 25 the escape of air therefrom.

Assuming that the main tank 1 has been supplied with air under pressure to its maximum operating pressure of eighty and four tenths pounds, and that the initial auxiliary 35 or variable pressure tank A is likewise charged with air at a pressure of eighty pounds, the apparatus is in initial condition for operation. This condition is indicated as the first stage, Fig. 2. It will be understood that the valves *a* to *j* and *a'* to *j'* are opened and closed in proper sequence and for proper intervals of time by suitable cam drums or shafts operated by the motor. In starting the apparatus it 45 will be necessary to operate the motor by hand or by external means through one cycle of operation in order to admit the air under pressure to the several cylinders to cause the motor to operate the valves 50 through succeeding cycles of operation.

The valves *c* and *e* being opened by the valve operating mechanism, the air under high pressure will flow from the auxiliary tank A through the conduit 27 to the valve *c*, then through the conduits 15 and 16 to the high pressure cylinder 3 and will be exhausted from the high pressure cylinder 3 through the conduits 18 and 17 to the valve *e* and then through the conduit 28 to the 55 inner end of the auxiliary tank B, the internal pressure of which is at normal atmospheric pressure. The air will continue to flow from the auxiliary tank A through the path traced including the high pressure cylinder 3 and into the low pressure tank

B until the pressures in the tanks A and B are equalized or forty pounds pressure in each tank. Inasmuch as the tanks are of equal capacity, the volume will thus be increased from two cubic feet to four cubic 70 feet and the pressure correspondingly lowered from eighty pounds to forty pounds. However, during this expansion of air from tank A to tank B the preponderance of air pressure in the tank A will have operated the high pressure cylinder 3, each succeeding stroke of the motor piston being under the influence of a decreased pressure. The capacity of the motor cylinder or the volume of its charge is so proportioned to 80 the capacity of the auxiliary or variable pressure tanks as to equalize the latter with few strokes whereby the auxiliary or variable pressure tanks will be caused to function with rapidity. 85

The pressures in the auxiliary tanks A and B having been equalized, a condition will be effected as indicated in the opposite side or series tanks A' and B', Fig. 1, which have equal pressure of forty pounds per 90 square inch and which constitutes the second stage of operation, Fig. 3. At this moment the valves *c* and *e* will be closed and the valves *a*, *g*, and *h* will be opened. Air will then flow simultaneously from both 95 containers A and B through the conduits 27 and 28 to the valves *g* and *h* and thence through the conduits 19 and 20 to the inlet ports of the low pressure cylinders 4-4 from which it is exhausted through the conduit 21 to atmosphere. At the same time a charge of air is admitted through the conduits 14 and 13 to the valve *a* and thence through the conduits 29 and 30 to the opposite side of the piston 23 in the auxiliary 100 tank B. This is the existing condition indicated on the low pressure side or series Fig. 1 or in the second stage of operation Fig. 3. The pressure of the incoming air at supply tank pressure upon the piston head drives 110 the pistons in unison toward the right in Figs. 1 and 3, causing the air to be discharged from the auxiliary tanks A and B simultaneously at constant pressure of forty pounds each. 115

It is to be noted that during the first stage of operation while the tank A is discharging into the tank B the pressure gradually falls from an initial pressure of eighty pounds per square inch to a final pressure 120 of forty pounds per square inch at which time the auxiliary tanks A and B equalize.

During the second stage of operation while both tanks A and B are simultaneously discharging through the low pressure 125 cylinders of the motor to atmosphere, there is no drop or decrease of pressure inasmuch as a new high pressure charge is being admitted from the supply tank into the auxiliary tank B on the opposite side of the pis- 130

ton at an initial pressure of eighty and four tenths pounds (80.4), gradually decreasing to a minimum pressure of eighty pounds per square inch which is counterbalanced by the pressure of forty pounds per square inch upon the opposite sides of each of the piston heads 22 and 23. The incoming high pressure charge therefore causes the pistons to move toward the discharge ends of the tank (see Figs. 3 and 4) to compensate for the discharged air and maintains the operating pressure of both tanks constant until both are entirely exhausted.

15 During this movement of the piston the tank A is being supplied with air at atmospheric pressure at the rear side of the piston through the intake or breathing tube 25 whereby at the completion of the second 20 stage the relation of the auxiliary tanks A and B will be reversed and tank B will contain a high pressure charge of eighty pounds per square inch while tank A will be at atmospheric pressure. The operation 25 before described is then reversed and during the third stage represented by Fig. 4 the tank B is discharged through the high pressure cylinder 3 into tank A until they are equalized. Tank B having received its full 30 high pressure charge, the valve *a* is closed and valves *g* and *h* which communicate with the discharged or exhausted ends of the auxiliary tanks A and B are also closed and the valves *d* and *f* are opened. The air under high pressure of eighty pounds per 35 square inch is then discharged from the tank B through the conduits 30 and 31 to the valve *d*, then through the conduits 15 and 16 to the high pressure cylinder 3 from 40 which it is exhausted through the conduits 18 and 17 to the valve *f* and through the conduits 32 and 33 to the auxiliary tank A then at atmospheric pressure. The air will continue to flow from the high pressure tank 45 B through the course last traced into the low pressure tank A until the tanks A and B equalize with a pressure of forty pounds per square inch each.

At the beginning of the fourth and last 50 stage of the cycle of operations the tanks are equalized as indicated in Fig. 5. It will be remembered that the pistons at this point in the cycle of operation are at the right, Fig. 1, and the tank charges are at the left 55 of the pistons and will be discharged through the left hand ends of the tanks. The valves *d* and *f* are then closed and the valves *b*, *i*, and *j* are opened. The charges of air from both tanks A and B at forty 60 pounds pressure are then discharged simultaneously through the conduits 30 and 33 to the valves *j* and *i* and then through the conduits 19 and 20 to the low pressure cylinders 4-4 from which the air is exhausted 65 through the conduit 21 to atmosphere.

At the same time a high pressure charge is admitted from the supply tank 1 through the conduits 14 and 13 to the valve *b* and then through the conduit 27 to the opposite side of the piston head 22. This high pressure charge being admitted at an initial pressure of eighty and four tenths pounds gradually decreasing to a final pressure of eighty pounds per square inch is counterbalanced by the opposing pressures of forty 70 pounds per square inch upon the opposite sides of both pistons causes the pistons to move toward the left to compensate for the discharge of air from both tanks at a constant pressure of forty pounds through the 75 low pressure cylinders 4-4 to atmosphere. The incoming high pressure charge by moving the piston to compensate for the discharge of the low pressure charge maintains the low pressure charges constant at forty pounds 80 pressure until both tanks are exhausted. During this movement of the pistons air has been admitted to atmospheric pressure through the inlet or breathing tube 25 and past the check valve 26 into the auxiliary 85 tank B to compensate for the movement of the piston.

At the completion of the last or fourth stage the auxiliary tank A will contain the high pressure charge of eighty pounds pressure 90 while the auxiliary tank B will be empty or at atmospheric pressure which completes the cycle of operation, leaving the tanks in the condition found at the beginning of the first stage.

While the description thus far applies to one side or series only, the same description is equally applicable to the other side or series by reading the same reference characters with the prime marks or exponents 100 which distinguish the characters and elements of one side or series from those of the other. The only difference between the operation of the two sides is that they operate in alternate relation, *i. e.*, while the 105 high pressure charge is being discharged from the auxiliary or variable pressure tank of one side through the high pressure cylinder 3 into the low pressure tank of the same side the auxiliary or variable pressure 110 tanks of the opposite side or series will be simultaneously discharged under equalized pressure through the low pressure cylinders 4-4 of the motor to atmosphere and vice versa.

115 In other words, while the primary side or series is performing the first series of the cycle of operations, the second side or series is operating in the second stage of the cycle and while the primary side or series operates through the second stage of its cycle of operations, the secondary side or series is operated through the third stage of its cycle of operations, etc. Thus while one side or series is supplying the high pressure 120

cylinder 3 the other side or series supplies the low pressure cylinders 4 and both high and low pressure cylinders are supplied alternately from opposite sides or series.

5 Each high pressure charge is thus utilized first from initial high pressure to half pressure through the high pressure cylinder 3 and then at half pressure but double volume through the low pressure cylinders 4-4 to 10 atmosphere.

To recapitulate the air is relayed through a succession of tanks from the main supply tank 1 to the motor. Initially air under high pressure is supplied from one 15 tank upon one side of the cistern through the high pressure cylinder to the second tank upon the same side while at the same time air at lower pressure is being supplied through the low pressure cylinders simultaneously from both tanks upon the upper 20 side of the cistern. The supply of air at higher pressure continues through the high pressure cylinder until the two tanks equalize whereupon the air is switched from 25 the equalizing tank simultaneously through the low pressure cylinders through atmosphere. Thus the high pressure cylinder 3 receives air under high pressure from the tank B and discharges it into the tank C 30 until the tanks A and B equalize while at the same time the cylinders 4 are receiving air simultaneously from the tanks A' and B'. By the time the low pressure tanks A' have been exhausted on their discharge side they 35 will have been recharged with high pressure supply from the tank 1 through the lines 13' and valves a' and b'. At this moment the initial cylinders A and B will have equalized and the air supply will have been 40 switched from the high pressure cylinder 3 to the low pressure cylinder 4 whereby the tanks which supplied the high pressure cylinder and received the discharge therefrom will then supply the low pressure 45 cylinders and one of the tanks which had previously supplied the low pressure cylinders, will now contain a charge at high pressure to supply the high pressure cylinder 3 which will discharge into the second 50 or corresponding tank of the same side, until these tanks are equalized. Thus they alternate in operation. One tank discharging through the high pressure cylinder into the other tank until these are equalized, and 55 then both discharging through the low pressure cylinders to atmosphere until exhausted, during which time one of the tanks has received a new high pressure charge. The opposite series of tanks being engaged 60 in the same cycle of operation but being differently timed.

The purpose or utility of the succession of tanks is to relay the air pressure through successions whereby it is twice used at different pressure. In the first instance it is

of high pressure and small bulk and in the second instance of increased bulk and low pressure.

As before stated, the supply tank and also each of the auxiliary or variable pressure tanks is insulated or jacketed to prevent so far as is possible the loss of heat incident to compression. The compression of the air within the supply tank will cause such air to be heated. This air in a heated condition is then admitted from the supply tank into the initial auxiliary or variable pressure tank and heats the walls thereof. The air is then discharged from this primary heated tank into the second tank of the same series or side. At the second succeeding stage, the air is discharged from the second tank which is then at high pressure, into the low pressure tank previously heated by the high pressure charge which takes up a portion of the heat from the walls of the tank or container which tends to compensate for the expansion of air and thereby maintain the air at even temperature or an isothermal condition. The expansion of the air in the previously heated container or tank and its consequent absorption of heat from the walls thereof to maintain the even or isothermal condition cools the tank somewhat preparatory to receiving the succeeding high pressure heated charge which again heats the walls of the container. Thus the walls or jacket of the tank or container absorbs from the high pressure charge a quantity of heat thereby lowering the temperature of the high pressure charge, which absorbed heat is given back to the low pressure charge subsequently received into the same tank or container thereby tending to raise the temperature of the low pressure charge to maintain the high and low pressure charges at comparatively even temperature.

Valve operating mechanism, compressors, and fluid pressure motors are common and well known in the art. Any suitable valve gear timed and arranged to operate the valve in proper sequence and at proper intervals of time may be employed.

From the above description it will be apparent that there is thus provided a device of the character described, possessing the particular features of advantages before enumerated as desirable but which obviously is susceptible of modification in its form, proportion, detail construction, or arrangement of parts without departing from the principle involved or sacrificing any of its advantages.

While in order to comply with the statute the invention has been described in language more or less specific as to certain structural features, it is to be understood that the means and construction herein described comprise but one mode of putting

the invention into effect and the invention is therefore claimed broadly in any of its possible forms or modifications within the scope of the appended claims.

5 Having thus described my invention, I claim:

1. In a fluid pressure system, a supply reservoir for fluid under pressure, a motor, auxiliary reservoirs arranged in pairs, connecting conduits between the supply reservoir and the auxiliary reservoirs, and between the auxiliary reservoirs and the motor, and a valve in each conduit, and means for automatically controlling said valve whereby the fluid under pressure will be discharged from the supply reservoir into the initial auxiliary reservoir, thence through the motor into the second auxiliary reservoir of the pair, thence simultaneously from both auxiliary reservoirs again through the motor to an area of low pressure or atmosphere.

2. In a fluid pressure system, a motor having high and low pressure sections, two reservoirs of substantially equal capacity, means for supplying fluid under pressure thereto, conduits connecting the reservoirs and the motor and a valve in each conduit and means for automatically controlling said valve whereby fluid will be discharged from the initial reservoir through the high pressure section of the motor into the second reservoir until the pressures of the reservoirs are substantially equal and then simultaneously from both reservoirs through the low pressure section of the motor to an area of lower pressure.

3. In a fluid pressure system, a motor having high and low pressure cylinders, primary and secondary reservoirs of substantially equal capacity, means for supplying fluid under pressure to said primary reservoir, conduits connecting the reservoirs and motor and a valve controlling each conduit, and means for automatically controlling said valve whereby the fluid under pressure will be discharged from the primary reservoir through the high pressure cylinder into the secondary reservoir until the pressure of the reservoirs is substantially equal after which the fluid will be simultaneously discharged from both reservoirs through the low pressure cylinder of the motor.

55 4. In a fluid pressure system, a motor having high and low pressure cylinders, two pairs of reservoirs and an independent series of valved conduits connecting each pair of reservoirs with the motor, means for supplying fluid under pressure through said valved conduits alternately to a reservoir of each pair and thence to the motor, and means for opening and closing the valved conduits in sequence, the construction and arrangement being such that the fluid

under pressure will be discharged from one reservoir through the high pressure cylinder into the second reservoir of the same pair until the reservoirs are under substantially equal pressure, the fluid under pressure being simultaneously discharged from both reservoirs of the second pair through the low pressure cylinder of the motor.

5. In a fluid pressure system, a source of supply for fluid under compression, a utilizing mechanism having high and low pressure sections, two containers for fluid under pressure, a series of valved conduits connecting each container with the source of supply and with the utilizing mechanism and through the utilizing mechanism with the other container and with atmosphere and means for opening and closing the valve conduits in predetermined sequence, interconnected pistons in the containers adapted to move in unison, the construction and arrangement being such that a charge of air or similar fluid being admitted at high pressure to one of the containers will be discharged therefrom through the high pressure section of the utilizing mechanism into the second container, the increased volume of fluid being then discharged simultaneously from both containers through the low pressure section of the utilizing mechanism to normal or neutral pressure, and a new high pressure charge will be simultaneously admitted at the opposite side of the piston into one of the containers to move said piston to compensate for the discharged fluid whereby the fluid remaining to be discharged is maintained under constant pressure, and an inlet for air at atmospheric pressure to each container to compensate for the movement of the piston therein.

6. In a fluid pressure system, a source of supply for fluid under pressure, a fluid pressure utilizing mechanism including high and low pressure sections, two containers for fluid under pressure, a piston in each container, inter-connecting means between the pistons whereby they will move in unison, means for admitting fluid under pressure to one of said containers, means for equalizing the pressure in the containers by discharging a portion of the high pressure charge of fluid from the said container through the high pressure section of the utilizing mechanism into the second container whereby said high pressure charge will assume increased volume at lower pressure, and means for thereafter simultaneously discharging both containers through the low pressure section of the utilizing mechanism, and means for admitting a succeeding high pressure charge to one of the containers at the side of the piston opposite the contents being discharged whereby the contents of both containers will be discharged at substantially constant pressure by the move-

ment of the piston under the influence of the incoming high pressure charge.

7. In a fluid pressure system, a source of supply for fluid under pressure, fluid pressure utilizing mechanisms, two containers for fluid under pressure, means for admitting fluid under pressure to one of said containers, means for discharging a portion of the contents of said container through one utilizing mechanism into the second container, means for discharging the contents of both containers simultaneously through another utilizing mechanism, the high pressure charge being admitted to the containers alternately.

8. In a fluid pressure system, a source of supply for fluid under pressure, a fluid pressure utilizing mechanism including high and low pressure sections, a plurality of containers for fluid under pressure, and a plurality of conduits connecting the containers with the source of supply and with the utilizing mechanism, said containers and conduits being arranged in two series or groups, means for admitting fluid under pressure alternately to a container of each series or group, the fluid under pressure being admitted alternately to the containers

of the same series or group, means for alternately discharging a portion of the contents of the charged container of each series or group through the high pressure section of the utilizing mechanism into a second container of the same series, means for alternately discharging the contents of the containers of each series simultaneously through the low pressure section of the utilizing mechanism, the discharge of one container into another and both containers simultaneously being effected alternately between the respective series or groups.

9. The herein described method of utilizing air or similar fluid under pressure which consists in expanding the fluid from a high pressure container through a utilizing mechanism into a low pressure container and then expanding the increased volume of fluid at lower pressure simultaneously from both containers through another utilizing mechanism to normal or neutral pressure.

In testimony whereof, I have hereunto set my hand this 27th day of June A. D. 1916.

GEORGE H. GROTH.
